(57) **CLAIM**

The ornamental design for a wire clamp, as shown and described.

DESCRIPTION

FIG. 1 is a front, top and right side perspective view of a wire clamp;

FIG. 2 is a right side elevation view thereof;

FIG. 3 is a top plan view thereof;

FIG. 4 is a left side elevation view thereof;

FIG. 5 is a bottom plan view thereof; and

FIG. 6 is a rear elevation view thereof;

FIG. 7 is a front elevation view thereof; and,

FIG. 8 is a front, bottom and left perspective view of the wire clamp.

The broken lines shown in the figures provide appropriate surface shading to clearly show the character and contour of all surfaces of the claimed design.
